SHANK REDUCING MACHINE

Charles E. Hood, Lynn, Mass., assignor to United Shoe Machinery Corporation, Flemington, N. J., a corporation of New Jersey

Application April 2, 1943, Serial No. 481,616

21 Claims. (Cl. 12—17)

This invention relates to machines for operating on soles and is herein illustrated and described as embodied in a shank reducing machine. There are two types of shank reducing machines in common use. In one type the sole is fed between a pair of matrix rolls to a knife which reduces the opposite marginal portions of the sole simultaneously. The matrix rolls, however, are expensive, and a machine must be equipped with several pairs to perform high grade work upon soles which vary considerably in size or style. The changing of the matrix rolls, furthermore, requires time and effort. In the other type of machine the sole is fed between a pair of rolls to a shank reducing knife while being held against an edge gage, this operation being performed in sequence upon the opposite lateral margins of the sole.

It is an object of the present invention to provide a shank reducing machine capable of operating simultaneously upon the opposite lateral margins of a sole without requiring expensive matrix rolls. The machine illustrated herein, furthermore, is capable of thus operating upon two soles simultaneously.

In accordance with a feature of the invention, the illustrated machine is provided with a pair of clamps for clamping the two soles, a set of knives for operating on the soles, and a common means for operating the clamps in unison and the knives in unison in timed relation to the operation of the clamps. The operating means consists of a cam mechanism which first causes the soles to be clamped and then moves the knives through their cutting strokes. The soles are thus held flat against a work table while the knives are operating, and because the soles are held flat the operation can be performed more accurately than would be possible if the soles were to be allowed to buckle, twist, or otherwise depart from their normal shapes while being fed past a stationary knife.

It is desirable to maintain each knife approximately at right angles to the portion of the sole edge upon which it is operating. Another feature of the invention consists, accordingly, in an arrangement for turning the knives to obtain this result. The knives are therefore mounted on spindles journaled in the knife carriers and rotated by a cam mechanism. While the knives are advancing from the heel end of each sole toward the ball line, the curvature of the sole edge is not sufficient to call for varying angles of the knives. At the ball line, however, the curvature is more pronounced. The illustrated machine, therefore,

is arranged to advance the knives of each pair simultaneously from the heel end of the sole to cause them to reduce the shank of the sole at the opposite lateral margins thereof, and then to turn the knives outwardly to cause them to emerge from the sole at the ball line.

It is necessary, as the knives advance, to impart a lateral component to their movement which will cause them to follow the curvature of the sole edges. This is accomplished, in the illustrated machine, by a spring mechanism which urges the knives inwardly toward the sole as far as permitted by gages on the knife blocks. These gages, in the illustrated machine, bear against the edges of the sole itself rather than against a templet shaped like the sole. Some advantages of thus gaging from the sole itself are the saving of the time and effort which would be lost in matching templets to fit the various soles, the saving of the cost of the templets (of which a large number would be required), and the attainment of greater accuracy, for even with a large number of templets the exact matching of any particular sole with a templet would be unlikely.

However, in dispensing with templets and gaging from the sole itself the inward pressure exerted by the gages against the sole must be kept fairly constant; if too great it will cause the edges of the sole to curl over; and if too little it will fail to keep the gages in contact with the sole. Such maintenance of constant pressure is rendered difficult by the variation in the width of a sole from the heel end to the ball line. This variation in the width of the sole, unless compensated for, would cause considerable variation in the flexing of, and consequently in the stress exerted by, the springs which hold the knife gages against the edges of the sole. One of the features of the present invention is to provide for holding the gages against the sole edges with fairly constant pressure, notwithstanding the variation in the width of the sole from the heel end to the ball line. The means for accomplishing this result, in the illustrated machine, comprises a pair of cam plates having guiding edges which are approximately parallel to the sole edges. The springs act against the knife guides through these plates; and since the edges of the plates are approximately parallel to the edges of the soles, very little change in the flexing of the springs will take place.

These and other features of the invention will be best understood and appreciated from the following description of one embodiment thereof,

selected for purposes of illustration and shown in the accompanying drawings, in which

Fig. 17 is an enlarged plan view of the mechanism for gaging the knives relatively to the edges of the soles and also of the mechanism for gaging soles upon a work table;

Fig. 18 is a diagram illustrating the sequence of operations in a cycle; and

Fig. 19 is a plan view of a sole which has been operated upon by the knives.

The illustrated machine as shown in Fig. 2 of the drawings is arranged to operate upon a left sole L and a right sole R simultaneously. These soles rest upon a work table 30 which constitutes the top closure of a frame or housing 32 (see also Fig. 1). Two notches 33 (Figs. 2, 6 and 17) are formed in the forward portion of the work table 30 to enable the operator to grasp the soles L and R between his fingers in positioning the soles upon the work table and in removing them after the operation. These notches also help the operator to center the heel ends of the soles. The soles are gaged at their toe ends by a pair of gages 34 and 36 respectively and are held down upon the work table 30 by a pair of clamps, one of which, indicated by the reference numeral 38, is shown in Figs. 6 and 8. The shank reducing operation is then performed by a pair of knives 40 and 42 (Fig. 3) for the left sole, and a similar pair of knives 41 and 43 (see also Fig. 17) for the right sole. These knives are advanced from an initial position rearward of the heel end of the sole to reduce or bevel the edges from the lines 44 and 46 (Fig. 19) to the corresponding edges of the sole.

Each of the toe gages 34 and 36 has a V-shaped work engaging notch which serves not only to limit the distance which the sole can be moved forwardly by the operator but also to center the toe end of the sole. These gages are freely slid-

able upon the surface of the work table 30, each gage being connected to an arm 48 by a pair of parallel links 50 and 52. As shown in Fig. 2 of the drawings, the left-hand toe gage 34 is thus connected to the left-hand end of the arm 48 and the right-hand toe gage 36 is thus connected to the right-hand end of the arm 48. The central portion of the arm 48 constitutes a hub 54 within which a shaft 56 (see Fig. 6) is freely rotatable. Pinned upon the adjacent end of the shaft 56 to rotate therewith is a sleeve 58 which carries a cam 60 having a peripheral slot. Secured upon the work table 30 is an upstanding pin 62 which engages the cam slot and which therefore upon the turning of the shaft 56 causes the shaft to advance or recede in the direction of its axis. The shaft 56 is supported for rotation within a sleeve 64 which is journaled in bearings formed in supporting frame members 66 and 68 secured upon and extending upwardly from the work table 30. The shaft 56 is turned by a knob 70 secured upon its forward end while the sleeve 64 is turned by a knob 72 upon its forward end. The knob 70 has a hub which bears against the outer face of the knob 72 to prevent relative movement between the sleeve 64 and the shaft 56 in one direction. The opposite end of the sleeve 64 carries a hub 74 which bears against the hub 54; and the hub 54 bears against the sleeve 58 and thus prevents relative axial movement between the sleeve 64 and the shaft 56 in the opposite direction. The hub 54 is likewise held from axial movement in one direction by the sleeve 58 and in the other direction by the hub 74. It is evident from the construction so far described that turning of the knob 70 will cause the cam 60 to turn and because of the reaction of the cam slot with the stationary pin 62 will result in axial movement of both the shaft 56 and the sleeve 64. Such axial movement will be transmitted through the hub 74 to the arm 48 and thence through the links 50 and 52 to effect adjustment of the toe gages 34 and 36 forwardly or rearwardly.

In order to provide for the proper gaging of different styles of soles, provision is made for varying the distances of the toe gages from a common center line which coincides with the axis of the shaft 56 and with the horizontal center-line of the machine. This is accomplished by connecting the gage 34 by a link 76 (Fig. 17) to an enlarged portion 78 of the hub 74. The link 76, at its left-hand end is pivotally connected to the toe gage 34 and at its right-hand end is pivotally connected to the enlarged portion 78 at a point above the axis of the shaft 56. The right-hand toe gage 36 is similarly connected to the hub 74 by a link 80 which, at its left-hand end, is connected to the enlarged portion 78 below the axis of the shaft 56 at a point diametrically opposite to the pivotal connection of the link 76. It is evident that by reason of the above described connections the turning of the knob 72 will cause the toe gages 34 and 36 to move closer together or further apart. Throughout the adjustments the proper orientation of the toe gages will be maintained by the sets of parallel links 50 and 52.

The remaining operations are performed by automatic power-driven instrumentalities which will now be described. The power is obtained from a motor 82 (Figs. 1 and 2) mounted upon a bracket 84 secured upon a side wall of the housing 32. A pair of belts 84 from the motor 82 drive a constantly running pulley 86 mounted

outside the frame 32 for free rotation on a shaft 96. One end of the shaft 96 is journaled in a bearing 87 carried by a bracket 88 secured to the rear wall of the housing 32, and the other end of the shaft 96 is journaled in a bearing carried by a gear housing 89 within the frame 32. The rear wall of the frame 32 has a suitable opening through which the shaft 96 extends. The pulley 86 has a hub 99 (Fig. 5) which contains the driving member of a clutch 92. The driven member of the clutch 92 is connected to a sleeve 94 which is keyed upon the shaft 96. The operator, by depressing a treadle 98 (see also Fig. 4), causes a treadle rod 100 to swing a clutch lever 102 and thereby to slide the sleeve 94 into clutch engaging position, thus coupling the shaft 92 to the rotating pulley 86. Rotation of the shaft 96 is transmitted through a worm 103 and a worm gear 105 to a cam shaft 104 which is journaled in suitable bearings 107 and 108 (Fig. 4) supported within the housing 32. Secured upon the shaft 104 is a cam 106 (Figs. 4 and 5) having a projection 109 which once in every revolution of the cam shaft will engage a roll 110 carried upon a control lever 112. Such engagement causes the control lever 112 to release the clutch lever which is thereupon moved into disengaging position by a spring 114. Rotation of the shafts 96 and 104 is thereupon stopped by a brake 116. Inasmuch as similar one-revolution clutch mechanisms are well-known in the art, a more detailed description of this portion of the machine will not be necessary.

The arrangements for mounting and operating the shank reducing knives 40 and 42 will now be described. Considering, for example, the knife 40 which operates on the outside edge of the left sole L, this knife has a cutting edge 132 (Figs. 9 to 16) and a shank 118 which is rigidly secured to a block 122. A transverse slot 119 (Figs. 11, 13 and 16) in the knife block 122 accommodates the shank 118 with sufficient clearance to permit certain adjustments of the knife which will be described later. The shank 118 is clamped to a cylindrical block 120 by a disk 121 through which extends a clamping screw 123 threaded into the block 120. A notch 125 (Fig. 12) is formed in the cylindrical block 120 to accommodate the shank 118. The shank 118 is thus gripped firmly between the disk 121 and the block 120 when the screw 123 is tightened. The cylindrical block 120 fits within a cylindrical recess 127 in the block 122. A threaded stem 129 extending from the outer end of the cylindrical block 120 carries a nut 124 and a washer 126 which bears against the block 122 around the recess 127. The cylindrical block 120 may be slid axially in its recess 127 to adjust the knife forwardly or rearwardly, as will be explained. Axial adjustment of the cylindrical block in its recess 127 is facilitated and rendered more accurate by the use of the nut and washer. The cylindrical block may also be rotated to obtain a combined adjustment of the height of the knife and the inclination of its cutting edge. However, the machine is provided with an arrangement, to be described later, for adjusting the height of the knife without affecting its inclination.

The cylindrical block 120 is firmly clamped in its adjusted position in its recess 127 by a draw bolt 130 which fits within a slot 131 in the block 122. The draw bolt 130 has a bore 133 to receive the block 120 and a threaded stem 135 passing through a square washer 137 and carrying a nut 139. The washer 137 fits within a recess counter-

sunk about the end of the slot 131. It is evident that tightening of the nut 139 on the stem 135 will develop a thrust against the washer 137 and a tension in the stem 135 which will clamp the cylindrical block 120 against the wall of its recess 127.

A presser foot 134 (Figs. 9, 11, 14 and 16) is positioned directly in advance of the cutting edge 132 of the knife. The exact amount of this advance is determined by the above-described axial adjustment of the cylindrical block 120. A slide block 136, which carries the presser foot 134 is guided for vertical movement within a dovetailed guideway formed in the block 122. A compression spring 138 housed within a recess formed in the block 136 and interposed between a crossbar 140 and the bottom of the recess urges the slide and the presser foot downwardly to hold the presser foot yielding upon the surface of the work. The crossbar 140 is secured to the block 122 by screws 142. A stop screw 144 is threaded into the block 122 and has a beveled end 146 which engages a beveled surface 148 formed on the slide 136. It is evident that the turning of the screw 144 will vary the downward limit to which the presser foot can be urged by the spring 138. The stop screw 144 is provided with a lock nut 150. The leading edge of the presser foot 134 is rounded off, as indicated by the reference numeral 151 on Fig. 16, to enable the presser foot to ride up over the edge of the sole as the block 122 advances. The adjustment of the screw 144 should be such as to bring the working face of the presser foot only slightly below the level of the sole.

The knife block 122 has an upstanding dovetail 152 which slides within a corresponding dovetail guideway formed in a block 154 (Figs. 1 and 3). Journaled in a carriage 156 for rotation about a vertical axis is a spindle 158 (Fig. 3) having a collar 160 firmly pinned upon its lower end. The guide block 154 is secured to and supported by the collar 160. The knife block 122 is urged outwardly or toward the left, as shown in Figs. 1 and 3, by a pair of relatively weak horizontally arranged compression springs 162 (see also Fig. 9). Each spring 162 engages a cup-shaped recess formed in a bracket 164 secured to the knife block 122 and at its right-hand end is received within a similar cup-shaped recess formed in a lug 166 carried by the guide block 154.

Heightwise adjustment of the knife is effected by means of a knurled nut 168 (Fig. 3) seated within a recess formed in the carriage 156, the end faces of the nut being engageable with the upper and lower walls of the recess, respectively. The nut 168 is threaded upon a screw 170 which is free to move heightwise in a bore formed in the carriage 156. The upper end of the screw 170 is secured to a lug 172 which extends laterally from a bushing 173 surrounding the spindle 158 and within which the spindle is journaled for rotation. The lower end of the bushing 173 bears against the upper end of the collar 160, and the upper end of the bushing bears against the lower face of a pinion 292 secured upon the upper end of the spindle for a purpose to be described later. It is evident that turning of the nut 168 will adjust the bushing 173, and hence the spindle 158, the collar 160, the block 154, the block 122, and the knife 40, upwardly or downwardly.

The carriage 156 is slidably mounted upon a bar 174 (Figs. 1, 3 and 6) extending forwardly and rearwardly along the horizontal center line of

the machine, the forward end of the bar being secured to the upright frame member 68 and the rear end of the bar being secured to the upright frame member 66. The bar 174 has a dovetail portion which fits within a corresponding complementary dovetail formed in the carriage 156.

The arrangement and mounting of the shank reducing knife 42, which operates upon the inner marginal portion of the sole L, is similar in all respects to the arrangement and mounting of the knife 40, as so far described, the knives and their supporting members being arranged symmetrically with respect to each other along the longitudinal center line of the bar 174. The knife 42 has a carriage 176 similar to and symmetrical with the carriage 156 and mounted upon the opposite side of the bar 174 by an interlocking dovetail. A presser foot 177 (Figs. 3 and 17), similar to the presser foot 134 is mounted on the carriage 176 in advance of the knife 42. The knives 40 and 42 and their respective carriages are advanced as a unit longitudinally of the sole, and for convenience, are secured together at their upper portions by a clamping bolt 178 (Figs. 1 and 3). However, because the shank-reducing cut should extend further from the heel end on the inside edge of the sole than on the outside edge, the inside knife 42 is set in advance of the outside knife 40. The extent of such advance may be varied by adjustment, the outer carriage 156 having a longitudinal slot 180 to permit such adjustment. The clamping bolt 178, which passes through the slot 180, may be loosened and the two carriages adjusted relatively to each other to provide the desired amount of advance of the knife 40 over the knife 42. The clamping bolt 178 is then tightened to bind the carriages together.

The operative movement of the shank reducing knives 40 and 42 is obtained by sliding the carriages 156 and 176 along the guide bar 174. Such movement of the carriages is accomplished through a link 182 (Figs. 1 and 2) pivotally connected at its forward end to the carriage 176 and at its rearward end to the upper end of a lever 184 (see also Fig. 4) extending from a sleeve 185 which rotates upon a stationary shaft 186. A pair of stationary brackets 188 and 190 support the shaft 186. Extending from the sleeve 185 is a crank arm 196 upon the outer end of which is a cam roll 198. Secured upon the cam shaft 194 is a disk cam 200 having formed in one of its faces a cam groove which engages the roll 198. It is evident that rotation of the cam 200 will rock the sleeve 185 through the arm 196 and that such rocking movement will be transmitted to the lever 184 to advance the knife carriages.

While the knife carriages and their operating mechanisms have been described in detail for the left sole L, it will be understood that a similar pair of knife carriages indicated generally by the reference character 202 (Fig. 2) have been provided for the right sole R. The carriages 202 for the right sole are advanced by a link 204 pivotally connected at its forward end to one of the carriages and pivotally connected at its rearward end to an upper end of an arm 206 which extends upwardly from the sleeve 185. It will be evident from the foregoing description that rotation of the cam 200 will cause the two pairs of knife carriages to advance in unison.

Because of the curved outline of the soles, as shown in Figs. 17 and 19, it is not sufficient merely to advance the knives longitudinally of the soles.

It is necessary, in order to obtain a uniform thickness of the reduced edge of the sole and also a uniform breadth of the shank reducing cut, to provide a component of movement of the shank reducing knives which is transverse with respect to the sole and which will result in causing the knives to follow paths conforming to the curvature of the sole edges. The mechanism for obtaining this result includes a lug 208 (Figs. 9, 11, 14 and 17) depending from each of the knife carriers. Each lug 208 has a smooth rounded surface 210 which engages the edge of the sole in advance of the knife to gage the knife relatively to the sole and which is yieldingly held in engagement with the sole edge by a spring mechanism. The lug 208 extends below the remaining portion of the block 122 (Fig. 14) and, since the lug must clear the work table 30, it determines the downward limit to which the block 122 can be adjusted. For conditions of intermediate or upper heightwise adjustment of the block 122 the lug 208 will therefore be somewhat above the surface of the work table; but the normal range of heightwise adjustment of the block 122 is small in comparison with the thickness of the ordinary sole, and since the lug bears against the edge of the sole in advance of the knife, there will be ample space on the sole edge above the level of the bottom of the lug 208 for the lug to bear against. If any unusual downward adjustment of the knife is desired, it can be obtained, as has already been pointed out, by rotating the cylindrical block 120 in its bearing. The knife, moreover may be one selected from a series of knives for its particular characteristics, such as the height and the slope of its cutting edge.

The spring mechanisms for yieldingly maintaining the knives in gaged relation to the sole edges are similar for the two soles, and it will be sufficient, therefore, to describe only one in detail. For example, the mechanism used in operating upon the left sole L. This mechanism comprises a pair of flat plates 212 and 214 (Figs. 2 and 17) which are slidably supported by the surface of the work table 30. These plates serve as guides or cams, the plate 212 having a guiding edge 216 which is approximately parallel to the outer edge of the shank and heel portion of the sole L, and the plate 214 having a guiding edge 218 which is approximately parallel to the corresponding portion of the inner edge of the sole L. The plate 212 is pivotally secured to a pair of parallel links 220 and 221 which are pivotally mounted in the work table 30 and which constrain the movements of the plate 212 to such positions as to maintain the guiding edge 216 always parallel to any of its previous positions. The plate 214 is similarly constrained to parallel movement by a pair of links 222 and 223. The link 220 (Fig. 17) is mounted upon a fulcrum pin 224 which extends downwardly through the work table 30 and upon the lower end of which is mounted an arm 226 (see also Fig. 1). A pin 228 extending from the arm 226 engages a slot 230 formed in one end portion of a rod 232. The opposite end of the rod 232 is pivotally connected to a sleeve 234 which is slidably mounted for axial movement on a stationary shaft 236. A pair of brackets 238 mounted on the under side of the work table 30 provide support for the shaft 236. Pivotally mounted upon the sleeve 234 by a pin 240 is a link 242, the free end of the link 242 being pivotally connected to a crank arm 244 which extends from a sleeve 246 (Fig. 1). A vertical stationary shaft 248 secured to the housing 32 provides a bearing

for the sleeve 246. A pair of collars 249 secured upon the shaft 248 hold the sleeve 246 against axial movement. A second crank arm 250 extending from the sleeve 246 carries a cam roll 252 (Fig. 4) upon its free end. Secured upon the cam shaft 104 is a cam 254 having a peripheral groove 256 which is engaged by the roll 252. Rotation of the cam 254 will rock the arm 244 through the sleeve 246 and will thus cause axial movement of the sleeve 234. When the sleeve 234 is thus moved toward the right from the position shown in Fig. 17, the end of the slot 230 will presently engage the pin 228, rocking the arm 226 and the link 220 in a counter-clockwise direction and drawing the plate 212 to the left away from the sole L. When the sleeve 234 on the contrary is moved to the left, the slot 230 will leave the arm 226 and the link 220 free to the action of a tension spring 258 secured at one end to an extension of the arm 226 and anchored at its other end to a pin 260 secured to the lower surface of the work table. The spring 258 is stronger than the springs 162 which urge the knife block 122 away from the edge of the sole. Extending downwardly from the knife block 122 is a pin 262 (Figs. 11 and 14) upon which is mounted a roll 264 (see also Fig. 17) engageable with the guiding edge 216 of the plate 212. When the sleeve 234 is moved to the left the spring 258 will overcome the springs 162 and will urge the knife block in its transverse guideway as far in the direction of the sole as permitted by the gage 208.

The guide plate 214 is yieldingly urged toward the left as viewed in Figs. 2 and 17 by a tension spring 266 secured at one end to an arm which is below the work table 30 and directly below the link 223, said arm being rigidly connected to the link 223 by a pin 225 extending through and journaled in the work table. The other end of the spring 266 is anchored to a pin 268 extending downwardly from the lower surface of the work table 30. The knife block for the carriage 176 is provided with a roll and a gage similar to the roll 264 and the gage 208 whereby the spring 266, which is stronger than the springs 162 for the carriage 176, will overcome these springs 162 and yieldingly urge the knife block and the knife 42 as far toward the sole as permitted by its gage. Extending from the sleeve 234 is a lug 270 engageable with an abutment (not shown) carried by the above-mentioned arm extending from the pin 225. When the sleeve 234 is moved to the left it will release the plate 214 to the action of the spring 266 and when the sleeve 234 is moved to the right the lug 270 will engage the abutment just mentioned and draw the plate 214 away from the sole.

When the sleeve 234 is moved to the left as shown in Fig. 17, the springs 258 and 266 will move the guide plates 214 and 216 toward each other and toward the sole L which is positioned between them, as far as permitted by the gaging lugs 208 on the knife blocks. However, the knife carriages at the beginning of the operation occupy a position at the forward end of their stroke as indicated in Fig. 2. When the knife carriages are in this position the gaging lugs are beyond the heel end of the sole and consequently cannot serve to limit the movement of the guide plates 216 and 214 under the influence of the springs 258 and 266. However, it is desirable to provide definite limits to the inward movement of the guide plates in order to insure that the gaging devices will come into contact with the opposite sides of the

heel rather than the back of the heel when the carriages begin to advance. Accordingly the illustrated machine is provided with a stop in the form of a disk 274 (Fig. 17) eccentrically mounted upon a pin journaled in the work table and having a head 276 by which the disk may be turned. The disk 274 engages a lug 278 formed on the link 221. A pair of guide marks 280 on the work table cooperate with a mark 282 on the eccentric disk to indicate the desirable limits of such adjustment. A similar device 284 is provided for the plate 214 and similar devices 286 and 287 are provided for the guide plates on the right-hand side of the machine.

15 The guide plates on the right-hand side are similar to those already described upon the left-hand side, the outer right-hand guide plate being operated through a slotted link 288 similar to the link 232 and the inner right-hand guide plate being operated by a lug 290 on the sleeve 234. Movement of the sleeve 234 to the left will release the right-hand guide plates to the action of their respective springs in the same manner as has already been described in connection with the left-hand guide plates.

20 In high grade work where a clean cut is desirable, the shank reducing knives should be maintained at approximately right angles to the sole edge and it therefore becomes necessary, because of the curvature of the sole edges, to rotate the knives. It is also desirable to rotate the knives outwardly at the end of their advancing stroke to cause them to emerge from the sole at the ball line and thus make a clean termination 25 of the shank reducing cuts. Such rotation of the knife 40 is accomplished through the previously mentioned pinion 292 (Figs. 1, 2, and 3) secured upon the upper portion of the spindle 158. A bar 294, slidably in a bearing 296 (Fig. 3) formed 30 in the carriage 156 and in a bearing 298 (Fig. 2) formed in the upright frame member 66, has formed in it rack teeth which engage the pinion 292. The rack bar 294 is advanced by a cam 300 (Fig. 4) on the cam shaft 104. The face of the 35 cam 300 has a groove which engages a roll 302 on the free end of a crank arm 304. The opposite end of the arm 304 is secured upon a hub 306 which turns upon the stationary shaft 186. A yoke 305 connects the hub 306 to a hub 307, also 40 on the shaft 186, and causes the hub 307 to turn in unison with the hub 306. Extending upwardly from the hub 307 is a crank arm 308 (see also Fig. 1) which at its upper end is pivotally connected to the rearward end of a link 310. The forward 45 end of the link 310 is pivotally connected to a crossbar 312 which is secured to the rack bar 294 and also to a similar and parallel rack bar 314 (Figs. 2 and 3) which controls the turning of the knife 42. The operation of the cam 300 thus 50 serves to advance the two rack bars in unison and to rotate the knives 40 and 42 in accordance with the design of the groove in the cam 300.

55 The mechanism for turning the knives which operate upon the right-hand sole R is similar to that already described for the left-hand sole L, and is operated through an upstanding arm 313 from the sleeve 306.

It is necessary during the performance of the shank reducing operation to maintain each of the soles firmly clamped against the surface of the work table 30. For this purpose a clamp is provided for each of the soles and, since these clamps and their operating mechanisms are similar, only the left-hand clamping members will be described 70 in detail. The clamp for the left-hand sole L

comprises a plate 316 (Figs. 6 and 8) having a downwardly extending portion 318 shaped to bear against the forepart of the sole L and a downwardly extending portion 320 shaped to bear against the heel portion of the sole. The relation of the sole-engaging portions 318 and 320 of the clamps to the soles is illustrated in Fig. 17, wherein the sole-engaging portions are indicated by broken lines. Secured upon the upper surface of the plate 316 are a pair of brackets 322 having notched end portions 324 which engage annular grooves formed in the lower portion of a pair of hollow plungers 326. These brackets serve to center the clamping members rather than to transmit the pressure of the plungers. The lower ends of the plungers are convexly rounded and bear against the upper surface of the plate 316. The clamping pressures are obtained by coil compression springs 328 housed within the hollow plungers 326. The lower end of each spring 328 bears against the bottom of the recess in the plunger within which the spring is housed. The upper end of each spring bears against an abutment 330 slidably within the recess of the clamping member and bearing against the lower surface of a slide bar 332. The upright frame members 66 and 68 and the supporting bar 174 are bored to provide a horizontal guideway for the slide bar 332. The supporting bar 174 is also bored to provide vertical guideways for the clamping plungers 326. The upper portion of each clamping plunger 326 is recessed to provide a pair of upstanding ears 334 which embrace the slide bar 332. Inasmuch as the slide bar is of fairly large diameter the portion passing between the ears 334 is slabbed off to provide a running clearance. Secured between the ears 334 and extending diametrically across each clamping plunger above the slide bar 332 is a pin 336 upon which is mounted a roll 338. The upper surface of the slide bar beneath each of the rolls 338 is notched to provide an inclined cam or wedging surface 340 engageable with the roll 338. Pivottally connecting the rearward end of the slide bar 332 and the upper end of an arm 342 is a link 344. The arm 342 (see also Fig. 4) extends upwardly from a hub 346 which is rotatable upon the stationary shaft 186. A yoke shaped crank 348 connects the hub 346 to a similar hub 350 also rotatable on the shaft 186. A crank arm 352 extending from the hub 350 carries a cam roll 354. A cam 356 secured upon the cam shaft 104 has formed in one of its faces a groove 357 which engages the roll 354. Rotation of the cam 356 serves to rock the arm 352 and the arm 342 to operate the slide bar 332. Fig. 6 shows the position of the clamping mechanism after the arms 352 and 342 have been rocked clockwise from normal position to move the slide bar 332 to the right, enabling the springs 328 to exert clamping pressure through the plungers 326. Continued rotation of the cam 356 in the direction indicated by the arrow in Fig. 6 will serve to hold the sole clamped long enough for the shank-reducing operation, and then to move the slide bar to the left to unclamp the sole.

The instrumentalities for clamping the right-hand sole R are similar to those already described for the left-hand sole and are operated by an upstanding arm 358 (Fig. 4) secured on the hub 350.

Before the beginning of the operation the machine should first be adjusted to the particular length and style of the soles to be treated. For long soles the knob 70 should be turned to adjust the toe gages 34 and 36 rearwardly while for short

soles, this knob should be turned in the opposite direction to adjust the toe gages forwardly. For soles having a pronounced inward swing, the gages 34 and 36 should be adjusted further apart by turning the knob 72 than for soles of only a moderate degree of swing. After performing these adjustments the operator inserts a pair of soles L and R into the machine, sliding the soles forwardly until their toe ends engage the appropriate gages. The notches 33 in the forward portion of the work table enable the operator to gage the lateral positions of the heel ends of the sole with sufficient accuracy. The operator then depresses the treadle 98 to start rotation of the cam shaft 104. The cycle of operations thus initiated is illustrated diagrammatically in Fig. 18. The first operation after the cam shaft has started to rotate is the clamping of the soles firmly against the work table through the mechanism associated with the cam 356. As soon as the soles have thus been clamped in position the cam 254 operates to release the left-hand guide plates 212 and 214 and also the corresponding right-hand guide plates. The guide plates of each pair thereupon under the influence of their associated springs move toward each other from the normal separated positions in which they were held by the cam 254 while the machine was at rest. Such inward movement of the guide plates is limited by the eccentrics 214 and 284 for the left sole and 286 and 287 for the right sole. The cam 200 thereupon causes the knife carriages to begin to advance until the lugs 208, which occupy the position beyond the heel end of the sole, come into engagement with the sides of the heel and thus gage the knife blocks laterally of the sole. The knife carriages continue to advance and the knives operate upon the lateral margins of the sole while the knife blocks are continuously gaged laterally by the edges of the sole. At the same time that the knife carriages begin to advance the cam 300 causes the rack bars 294 and 314 of the left-hand knife carriages to advance and also the corresponding rack bars of the right-hand knife carriages. The advance of the rack bars takes place at the same rate of speed as the carriages, holding the knives against rotation, until each knife reaches a position adjacent to the ball line of the sole. The knife carriages thereupon stop while the rack bars continue with the result that each knife is rotated about the spindle which carries its supporting block. The operation of the knives is illustrated in Fig. 19 wherein the lines 441 and 443 represent the positions of the edges of the knives 41 and 43 when the inside knife 43 first makes contact with the heel end of the right sole R and wherein the lines 541 and 543 represent the positions of the knife edges at the end of the advancing movements of their carriages but before the knives begin to rotate. The lines 641 and 643 represent the paths of travel of the axes of the respective knife spindles. The advance of the inside knife 43 over the outside knife 41 is shown in each pair of lines. The lines 741 and 743 represent the positions of the knife edges at the limits of their rotations. It will be apparent from Fig. 19 that the rotations of the knife blades will serve not only to maintain the knife edges substantially at right angles to the edges of the sole at the localities of greatest curvature, but also to terminate the shank reducing cuts and bring the knives out of contact with the sole at the ball line, indicated on Fig. 19 by the broken line B.

The knives, after the completion of their opera-

tive movements, are held stationary for a brief pause or dwell during which the clamps (as shown in Fig. 18) are released to enable the operator to remove the soles from the machine. The guide plates are also automatically separated to their normal positions during this dwell. The remainder of the cycle consists in rotating the knives back to their normal angular positions and in returning the knife carriages to their forward or normal positions. The cycle of operation is now complete and the automatic one-revolution clutch mechanism operates to stop rotation of the cam shaft.

It has already been mentioned that, in the illustrated machine, the knives are held against rotation during the advance of the knife carriages, and are then rotated while the knife carriages are stationary. Such control of the rotation of the knives results in a sufficiently close approximation of the desired right-angled relation between the edges of the knives and the edges of the sole. However, it will be readily understood that the rotation of the knives by the operation of the cam 300 is independent of the advance of the knife carriages by the operation of the cam 200, and that by a suitable change in the design of the cam 300 the rack bars which rotate the knives may be advanced differentially with respect to the knife carriages rather than in unison with them. Any desired variation in the rotation of the knives relatively to their advancing movement may be obtained by appropriate design of the cams 200 and 300.

A relatively short sole R' is also shown in Fig. 19 for purposes of comparison with the longer sole R. The toe gages 34 and 36 should be adjusted forwardly by turning the knob 70 until the ball line of the short sole coincides with the position previously occupied by the ball line B of the longer sole. Such adjustment may be facilitated by providing suitable calibrations for size on the knob 70, these calibrations being so spaced as to bring the ball lines of soles of all sizes to the same locality on the machine.

Having thus described my invention, what I claim as new and desire to secure by Letters Patent of the United States is:

1. In a machine for performing a cutting operation along the marginal portion of a sole, a single-bladed knife, a sole support having a substantially plane working surface, means for advancing the knife along the edge of a sole on said support to cause the knife to cut progressively along the sole margin, and means for turning the knife in timed relation to the advancing means about an axis substantially normal to the plane of said sole support to maintain the cutting edge of the knife substantially at right angles to the edge of the sole.

2. In a shank reducing machine, a work table, a pair of single-bladed knives for operating upon the opposite marginal portions of a sole on said work table, means for advancing the knives along the opposite edges of the sole to cause the knives to make shank reducing cuts, and means for turning each knife in timed relation to the advancing means about an axis substantially normal to said work table to maintain the cutting edge of the knife substantially at right angles to the edge of the sole upon which it operates.

3. A shank reducing machine, comprising means for holding a sole, a pair of shank reducing knives, means for advancing said knives simultaneously from the heel end of the sole to cause them to reduce the shank of the sole at the

opposite lateral margins thereof, said advancing means being constructed and arranged to stop when the knives are in the vicinity of the ball line of the sole, and means for turning the knives outwardly to cause them to emerge from the sole at the ball line after the stopping of the advancing means.

4. In a machine for beveling the marginal portion of a sole, a work table for supporting a sole, a knife, a block for holding the knife, a carriage in which said block is mounted for rotation about an axis perpendicular to the work table, means for advancing the carriage relatively to the sole to cause the knife to make a beveling cut, and means for rotating the block about said axis to maintain the cutting edge of the knife substantially at right angles to the edge of the sole.

5. In a shank reducing machine, a pair of knives for operating upon the opposite marginal portions of a sole, means for advancing the knives relatively to the sole to cause them to make shank reducing cuts, a pivotal connection between each knife and said advancing means for enabling the knives to rotate in the plane of the sole, a cam, and mechanism operated by said cam to rotate said knives to maintain their cutting edges substantially at right angles to the edges of the sole at the curved shank portions.

6. In a shank reducing machine, a work table for supporting a sole, a clamp for holding the sole against said work table, a knife block, a shank reducing knife mounted in said knife block, a pivotal support for enabling said knife block to rotate about an axis perpendicular to said work table, said support being constructed and arranged also to enable the knife block to move toward and away from the edge of the sole, a gage on the knife block engageable with the edge of the sole, means for yieldably urging the knife block toward the sole as far as permitted by said gage, means for advancing the pivotal support to cause the knife to perform its shank reducing operation, and means for rotating the knife block about said pivotal support to maintain the cutting edge of the knife substantially at right angles to the edge of the sole at the curved shank portion.

7. In a machine for performing a cutting operation along the marginal portion of a sole, a support for a sole, a knife, means for causing relative movement between the sole support and the knife to cause the knife to operate progressively along the marginal portion of the sole, a gage associated with said knife to gage the knife laterally of the sole, a spring for yieldingly holding the gage against the edge of the sole as the knife progresses, and means for maintaining the stress of said spring substantially constant notwithstanding the considerable degree of movement of the gage laterally of the sole caused by the curvature of the sole edge as the gage progresses.

8. In a shank reducing machine, a sole support, a shank reducing knife, a guide approximately parallel to the edge of the sole, a spring urging said guide toward the sole, gaging means associated with the knife and engageable simultaneously with the edge of the sole and the guide to maintain the knife in gaged relation to the sole under the influence of the spring-pressed guide, and means for advancing the knife with its gaging means relatively to the sole and the guide to cause the knife to perform its cutting stroke, the guide serving by reason of its approximately parallel relation to the edge of the

sole to eliminate excessive flexing of the spring as the knife advances, thereby insuring a substantially constant gage pressure against the edge of the sole.

9. In a shank reducing machine, a sole support, a shank reducing knife, a guide having an edge approximately parallel to the edge of the sole, a pair of parallel links pivotally connected to said guide, a fixed pivot about which each of said links may swing, said links serving to constrain the guide to parallel movement toward and from the sole, a spring urging the guide toward the sole, gaging means associated with the knife and engageable simultaneously with the edge of the sole and the edge of the guide to maintain the knife in gaged relation to the sole under the influence of the spring-pressed guide, and means for advancing the knife together with its gaging means relatively to the sole and the guide to cause the knife to perform its cutting stroke, the guide serving by reason of its approximately parallel relation to the edge of the sole to eliminate excessive flexing of the spring as the knife advances, thereby insuring a substantially constant gage pressure against the edge of the sole.

10. A sole fitting machine, comprising a support for a pair of soles, a plurality of clamps for clamping the soles on said support, a plurality of knives for operating on the soles, and a common means for operating said clamps in unison and said knives in unison in timed relation to the operation of said clamps.

11. A sole fitting machine, comprising a support for a pair of soles, clamps for clamping the soles on said support, knives for operating on the soles, a driven cam shaft, a cam on said shaft, operating connections between said cam and said clamps, another cam on said shaft, and operating connections between said other cam and said knives, said cams being designed first to cause the soles to be clamped to the support, then to operate the knives, and then to cause the soles to be released.

12. A sole fitting machine, comprising a sole support, a clamp for clamping a sole upon said support, a pair of shank reducing knives for operating upon the opposite lateral edge portions of the sole, and cam-controlled mechanism for operating the clamp and the knives first to cause the clamp to clamp the sole upon the support, then to cause the knives to advance simultaneously in operative relation to the sole, and finally to cause the clamp to release the sole.

13. In a sole fitting machine, a pair of tools operable simultaneously on the lateral margins of a sole, relatively weak yieldable means for urging said tools apart to an inoperative position to facilitate the insertion of a sole between them and the removal of the sole, relatively strong yieldable means for urging said tools toward each other to an operative position, means for limiting the movement of the tools toward each other to position the tools in relation to the edge of the sole, and control means for rendering the relatively strong yieldable means operative and inoperative.

14. In a shank reducing machine, a pair of shank reducing knives operable simultaneously on the lateral margins of a sole, relatively weak resilient means for urging said knives apart to an inoperative position to facilitate the insertion of a sole between them and the removal of the sole, relatively strong resilient means for urging said knives toward each other to an operative position, means for limiting the movement of the

knives toward each other to position the knives in relation to the edge of the sole, control means for rendering said relatively strong resilient means operative and inoperative, and means for effecting relative movement between the sole and the knives in a direction longitudinal of the sole to cause the knives to make shank reducing cuts while the distance of the knives apart is controlled by said movement-limiting means.

15. In a shank reducing machine, a work table, a shank reducing knife, a carriage for said knife, a pivotal connection between said knife and said carriage for enabling the knife to turn about an axis substantially normal to said work table, means for moving said carriage to cause the knife to make a shank reducing cut on a sole on said work table, and means for turning the knife about said axis to maintain the cutting edge of the knife substantially at right angles to the edge of the sole.

16. In a shank reducing machine, a work table, a shank reducing knife for operating on a sole on said work table, a slide on which said knife is mounted, a block having a guideway for said slide, a carriage for said block, means for moving said carriage to cause the knife to make a shank reducing cut on the sole, a pivotal connection between the block and the carriage for enabling the knife to turn about an axis substantially normal to the work table, means for turning the knife about said axis to maintain the cutting edge of the knife substantially at right angles to the edge of the sole, and means for controlling the position of the slide in the guideway to maintain the knife in a desired relation to the edge of the sole.

17. In a shank reducing machine, a work table, a shank reducing knife for operating on a sole on said work table, a slide on which said knife is mounted, a block having a guideway in which said slide is movable in a direction parallel to the work table, a carriage for said block, means for moving said carriage to cause the knife to make a shank reducing cut on the sole, a pivotal connection between the block and the carriage for enabling the knife to turn about an axis substantially normal to the work table, means for turning the knife about said axis to maintain the cutting edge of the knife substantially at right angles to the edge of the sole, a gage engageable with the edge of the sole for controlling the position of the slide in the guideway to maintain the knife in a desired relation to the edge of the sole, and a spring for holding said gage yieldingly against the edge of the sole.

18. In a shank reducing machine, a work table, a shank reducing knife for operating on a sole on said work table, a carriage for said knife, means for moving the carriage to cause the knife to make a shank reducing cut on the sole, a spindle journaled in said carriage for rotation about an axis normal to said work table, means for supporting the knife on said spindle, a gear on said spindle, a rack meshing with said gear, and means for moving said rack at a rate which may differ from the rate of movement of the carrier, such difference in rate serving to rotate the spindle to maintain the cutting edge of the knife substantially at right angles to the edge of the sole as the knife progresses along the sole.

19. In a shank reducing machine, a work table, a shank reducing knife for operating on a sole on said work table, a carriage for said knife, a rotary driven cam, a driving connection from said cam for moving the carriage to cause the knife to make a shank reducing cut on the sole, a spindle

journaled in said carriage for rotation about an axis normal to the work table, means for supporting the knife on said spindle, a gear on said spindle, a rack meshing with said gear, a second rotary driven cam, and a driving connection from said cam for moving said rack at a rate to control the angular position of the edge of the knife about the axis of the spindle and thereby maintaining the edge of the knife in a desired angular relation to the edge of the sole.

20. In a shank reducing machine, a support for a sole, a shank reducing knife for operating on a sole on the sole support, means for moving the knife longitudinally of the sole to cause the knife to make a shank reducing cut on the sole, said moving means being constructed and arranged to permit the knife a component of movement transversely of the sole, a gage associated with the knife and engageable with the edge of the sole to guide the knife, a plate having an edge approximately parallel to the edge of the sole, resilient means urging said plate toward the sole, and a member associated with said knife and engageable with said edge of the plate to urge the knife under the influence of said resilient means as far as permitted by said gage.

5 21. In a shank reducing machine, a support for a sole, a shank reducing knife for operating on a sole on the sole support, means for moving the knife longitudinally of the sole to cause the knife to make a shank reducing cut on the sole, said moving means being constructed and arranged to permit the knife a component of movement transversely of the sole, a gage associated with the knife and engageable with the edge of the sole to guide the knife, a plate having an edge approximately parallel to the edge of the sole, a relatively strong spring urging said plate toward said sole, a member associated with said knife and engageable with said edge of the plate to urge the knife under the influence of the spring as far as permitted by the gage, means for retracting said plate against the opposition of said spring to facilitate of the removal of a sole from the support and the introduction of another sole, and a 10 relatively weak spring urging said knife away from the sole as far as permitted by said plate when the plate is retracted.

CHARLES E. HOOD.
